ROTARY VALVE FOR INTERNAL COMBUSTION ENGINES

John Brown and Edward Brown, Wednesbury, England

Application November 9, 1937, Serial No. 173,684
In Great Britain November 11, 1936

6 Claims. (Cl. 123—190)

This invention comprises certain improvements in or relating to rotary valves for internal combustion engines.

By this invention a continuous circulation of oil is fed into a recess in the rotary valve to cool the valve. A continuous circulation of oil is also fed to the bearing surface of the rotary valve and the oil is directed from inlet ducts to outlet ducts, into which latter ducts the oil is directed by the sealing pad aforementioned.

Referring to the drawings:

Fig. 1 is a cross sectional elevation of a cylinder head of an internal combustion engine having a rotary valve mechanism constructed according to this invention.

Fig. 2 is a section of the cylinder head on line II—II of Figure 1, the rotary valve being shown in full lines.

Fig. 3 is a section on line III—III of Figure 2.

Fig. 4 is a perspective view of the sealing pad.

Fig. 5 is a perspective view of the spring ring for bearing on the sealing pad.

Fig. 6 is a perspective view of the sealing ring.

Figs. 7 and 8 are respectively end views of the split ends of the sealing ring.

Fig. 9 is a perspective view of the oiling pad, and

Fig. 10 is a section through the cylinder head with the rotary valve removed, the section being taken on line X—X of Figure 3.

According to a convenient embodiment, the invention is applied to a single cylinder air cooled motor cycle engine. The detachable head 1 has a cylindrical bore for receiving a cylindrical rotary valve 2 which is fixed in position by the lock nut 3 which bears against the bearing ring 4 slidably but non-rotatably mounted in the cylinder head 1. An oil seal is formed by a metal ring 5 which is clamped between the bearing ring 4 and the cylinder head 1 at its outer periphery and spring pressed at its inner periphery against the shoulder 6 on the rotary valve. The rotary valve is driven by a bevel gearing 7 and 8.

The detachable head 1 has a port having a conical seating 9 for receiving a sealing ring 10. The sealing ring 10 is formed of cast steel or other metal and has a conical outer circumference for bedding against a conical seating 9 around the port. The inside face of the ring curves inwardly from the flat seating 12 to the inner edge of the conical outer wall. The ring is split and stepped so that the split ends overlap. Preferably for this purpose an inclined face 13 is cut on one side of the ring from a point below the middle of the conical outer wall to the flat seating

12, while the other part has a similar inclined face 14, the inclined faces sliding on one another as the split ring expands or contracts. A sealing element 15 is interposed between the sealing ring 10 and the cylindrical surface of the rotary valve 2, the sealing element being let into a recess in the detachable head. The sealing element has a port 16 therein which registers with the inlet and exhaust ports in the rotary valve as such valve rotates, and a surrounding surface 17 which forms a sealing surface around the port. The sealing element is pressed against the valve 2 by means of a spring 18 (Figure 5). The sealing ring 10, not only expands radially under spring tension but also tends to slide up the conical seating 9 to press against the flat outer surface of the element 15.

The exhaust port 19 in the valve is fitted with a pipe 20 which is heat insulated from the body of the valve by means of asbestos lining 21. The pipe 20 has a spout 22 to prevent formation of carbon. The exhaust port passes from one end of the rotary valve whilst the inlet port 11 passes from the other end.

During the firing stroke one side of the valve is subjected to considerable heat and this side has an oil cooling chamber 23 through which oil constantly circulates. A groove 24 is formed in the cylinder head around the periphery of the bearing ring 4 and this groove is in communication with a non-return valve spring ball controlled oil inlet 25. The groove 24 is placed in communication with an annular groove 26 in the internal surface of the bearing ring 4 by means of passages 27 and the groove 26 is placed in communication with the chamber 23 by means of the passages 28. The chamber 23 is divided by a central partition 29 and the passages 28 lead to one side of this partition. Outlet passages 30 lead from the chamber 23 on the other side of the partition 29 and such passages 30 lead to an annular groove 31 in the bearing ring 4. This groove 31 communicates by way of passages 32 with a passage 34 returning the oil to the source of supply. The oil is thus continuously circulated through the cooling compartment 23 while the bearing ring 4 is also efficiently lubricated.

In order to lubricate the cylindrical wall of the rotary valve by means of a constantly circulating flow of oil, a lubricating pad 35 is pressed against the wall of the valve, this pad has two end limbs 36 having oil ducts 37 which emerge from the raised portion 38 bearing in the annular grooves 39 in the cylindrical valve. The lubricating pad 35 has a U-shaped passage 39a

which communicates with the flow and return pipes 40 and 41 which communicate with ducts 42, 42a in a bridge piece 43 fixed to the cylinder head. The pipes 40 and 41 spring support the 5 lubricating pad 35 and such pad 35 is pressed on the valve 2 by means of a member 44 pressed outwardly by means of a spring 45, the pressure of which may be adjustable to govern the film of oil supplied through the ducts 38. The duct 10 42 is in communication by means of the passage 46 with the oil supply entering the valve 25, whilst the duct 42a returns the oil to the source of supply. The lubricating pads have inclined 15 projections 47 which scrape the oil passed through the ducts 38 inwardly of the rotary valve, the rotary valve rotating in the direction from the scrapers 47 to the ducts 38. The bearing surface of the cylinder head is provided with inclined oil channels 48 which collect the oil 20 from the surface of the rotary valve and direct the same towards the centre of the valve. These grooves 48 are shaped to scrape the oil into the grooves. The oil therefore is caused to flow towards the centre of the rotary valve and the 25 sealing element 15 forms a scraper and causes the oil to flow away through the ducts 49 into the annular groove 50 which is in communication with the duct 51 for returning the oil to the source of supply. The continuous flow of oil 30 therefore lubricates the bearing surface of the rotary valve, whereby oil is prevented from burning and carbonizing. Annular grooves 55 are formed in the cylinder head on each side of the valve and these annular grooves are in communication with the groove 50 so that any oil which flows outwardly on the rotary valve will also be returned to the source of supply.

The outer end of the rotary valve on the inlet side is sealed by means of a rubber ring 52 40 which is pressed between the washer and a casting 53 by means of a spring ring 54.

We claim:

1. A rotary valve mechanism comprising a cylinder head, a rotary cylindrical valve mounted in the cylinder head, a bearing ring or member on one side of the valve and fitted in an annular recess in the cylinder head, an annular oil duct surrounding the periphery of the bearing member, two annular ducts around the internal periphery of the bearing member, and ducts in the wall of the valve for registering with ducts leading to the respective annular ducts or the interior of the bearing member for the feed and return flow of oil to an interior chamber in the 55 valve for cooling the valve.

2. A rotary valve mechanism comprising a cylinder head, a rotary cylindrical valve mounted in the cylinder head, a bearing ring or member on one side of the valve and fitted in an annular recess in the cylinder head, an annular oil duct surrounding the periphery of the bearing member, two annular ducts around the internal periphery of the bearing member, and ducts in the wall of the valve for registering with ducts leading to the respective annular ducts or the interior of the bearing member for the feed and return flow of oil to an interior chamber in the 60 valve for cooling the valve, which cooling cham-

ber is behind that portion of the valve which closes the combustion chamber during the firing stroke.

3. A rotary valve mechanism for internal combustion engines, comprising a cylinder head, a cylindrical rotary valve mounted in the head, and means for feeding oil to the bearing surface of the valve wall comprising an oiling-pad pressed against the wall of said cylindrical valve and having an oil duct or ducts fed from a continuous 10 circulating stream of oil which oil duct or ducts open directly on the wall of the valve, and scraper devices and oil channels for directing the oil from the feed ducts over the surface of the rotary valve to outlet ducts leading the oil back to the 15 source of supply.

4. A rotary valve mechanism for internal combustion engines, comprising a bore in the cylinder head, a cylindrical rotary valve mounted in the bore, an oiling pad, a spring device for pressing the oiling pad against the wall of the rotary valve, and means for feeding oil to the bearing surface of the valve wall, said oiling pad having an oil duct fed from a continuous circulating stream of oil which oil duct opens directly 20 on the outer surface of the valve, and a scraper device and oil channels for directing the oil from the feed duct over the surface of the rotary valve to outlet ducts leading the oil back to the source 25 of supply.

5. A rotary valve mechanism for internal combustion engines, comprising a bore in the cylinder head, a cylindrical rotary valve mounted in the bore, an oiling pad, a spring device for pressing the oiling pad against the wall of the rotary 30 valve, and means for feeding oil to the bearing surface of the valve wall, said oiling pad having an oil duct fed from a continuous circulating stream of oil which oil duct opens directly on the outer surface of the valve, a scraper device on the oiling pad for diverting the oil centrally of the valve and oil channels in the bore of the cylinder head for causing the oil to flow towards the centre of the valve.

6. A rotary valve mechanism for internal combustion engines, comprising a bore in the cylinder head, a cylindrical rotary valve mounted in the bore, an oiling pad, a spring device for pressing the oiling pad against the wall of the rotary valve, and means for feeding oil to the bearing surface of the valve wall, said oiling pad having an oil duct fed from a continuous circulating stream of oil which oil duct opens directly on the outer surface of the valve, a scraper device on the oiling pad for diverting the oil centrally 45 of the valve, and oil channels in the bore of the cylinder head for causing the oil to flow towards the centre of the valve, a sealing element bearing against the wall of the rotary valve having 50 ducts at the side for leading oil from the wall of the cylinder to return such oil to the source of supply, and a sealing ring forming a gas tight seal with a sealing in the port leading from the combustion chamber and a gas tight seal with the said sealing element.
